UNITED STATES PATENT OFFICE

LEONARD R. CARLEY, OF WATERTOWN, AND WALTER T. ABEL, OF WATERVILLE, CONNECTICUT, ASSIGNEES TO THE PATENT BUTTON COMPANY, OF WATERBURY, CONNECTICUT, A CORPORATION OF CONNECTICUT

BUTTON

Application filed September 2, 1931. Serial No. 560,796.

Our invention relates to new and useful improvements in buttons and particularly to the little die or vise of the button in which the tack or fastener is curled.

5 One of the objects of the present invention is to provide a button comprising a shell with integral hub; a die and a cap, on which latter there will be any desired insignia, the little die in turn being so formed that it will 10 curl the prong or fastener, rather than just blunt or deform the same.

Many of the buttons in use today for overalls or work garments of other kinds have the cap stamped with a trade name and fanciful design, and as part of this stamping extends above the normal outer surface of the button, it will permit the use of a die that also extends above the normal inner surface of the cap, and will allow the button to be fastened in place (by a plunger in the automatic attaching machines) without having the top of the die mar the insignia or stamping on the cap of the button.

Still another object of the invention is to 25 provide a small die having a domed upper surface to thus assure that the tack or prong fastener will be properly curled within the die when inserted, rather than just blunted and at the same time will not mar the raised 30 or figured surface of the button when the button is attached in the ordinary attaching machine.

With these and other objects in view, the 35 invention consists in certain new and novel arrangements and combination of parts as will be hereinafter more fully described and pointed out in the claims.

Referring now to the drawing, showing a 40 preferred embodiment,

Fig. 1 is a view of the dome shaped die forming the gist of the present invention;

Fig. 2 is a view of the shell having the perforate integral hub;

Fig. 3 is a sectional view showing the dome shaped die fitted within the shell;

Fig. 4 is a sectional view on line 4-4 of Fig. 5 showing a button with a stamped cap completing the button assembly, the prong fastener holding the button tightly to the 50 cloth, and

Fig. 5 is a top plan of a cap.

Referring now more particularly to the several views, and for the moment to Fig. 2, there may be seen the conventional type of metal shell 1, having the integral hub 2, which 55 may be perforate as at 3, and the usual body portion 4 with the outwardly extending flared rim 5, over which a cap 6 (see Fig. 4) is crimped. However, before the cap is 60 crimped in position a small die or vise 7 is 65 to be inserted, which die is clearly illustrated in Fig. 1.

This small die is preferably made of ribbon steel and may be .025 inches greater in 70 length than in width. The die tapers slightly towards its bottom, so as to snugly fit within the hub 2 of the shell and it will also be noticed that there is a small peripheral shoulder or rim 8 near the upper edge of the die that is designed to extend against or slightly 75 over the upper edge of the inner walls of the hub, as may be seen in Fig. 4.

Now the die is provided with an integral top or wall 9 which is dome shaped as may be clearly seen from the several views. The 80 radius of the dome is slightly less than say one-half the inside diameter of the hub of the button. The bottom wall 10 of the die may be perforated as at 11, so that when the die is placed in position this perforation 11 85 will align with the perforation 3 in the shell to thus help guide the prong of the fastener when it is driven up within the die.

To assemble the button the die will be 90 driven within the hub 2 after which the cap 6 will be crimped in the usual manner about the flared rim 5.

Now the cap may have raised stampings, (letter or design) thereon and in Fig. 4 we 95 have shown the raised portions 12, which designate the elevated letterings that might be stamped on the cap.

It will be noticed that there is a centrally raised portion 13 of the cap and this raised portion may be the raised stamping of any 98 desired insignia formed on the top of the button, and we do not wish to be limited to the exact lettering or cross section of raised portion shown in the cap.

It will be noticed that the extreme top of 100

the dome 14 extends above the lower top surface of the cap and just contacts with the raised portion 13 of the cap.

Now as may be seen in Fig. 4, when a tack 5 15 is driven through the cloth 16 and into the little die 7, the prong 17 of the tack will strike against the inner top surface of the dome and be properly curled down into the position as shown in Fig. 4 to thus tightly 10 hold the entire button structure in place.

There are numerous advantages in having this die dome shaped, as where little flat dies are used, the prong of the tack will be blunted or deformed, rather than properly curled, 15 and the pressure on the die would be much greater than where the tack prong is properly curled when impinging against the top surface of the die.

Again, it is possible to use this dome shaped 20 die in buttons with a flat top, but when the buttons are attached and the plunger (not shown) rests on the top of the button and the tack is forced up into the die, it will mark or score the flat cap and may slightly raise the 25 top surface of the cap and slightly disfigure the same. However, where the cap is ornamented with stampings, the little dome shaped die will not mar the cap and even if there were a slight score or raised portion, 30 it is not apt to be noticeable nor will it be great enough to in any way spoil the configuration.

Lastly, by having the die dome shaped, it will help support the ornamented cap, that 35 is, it will prevent it from sagging in the center.

In actual use we have found that by forming this little die with the domed head, the tack or fastener will properly curl within the 40 die to thus make a rigid connection and there will not be as great a force against the upper surface of the die as when a flat shaped die is used, due to the proper curling of the tack impinging with the upper surface of the die.

Having thus described our invention, what 45 we claim as new and desire to secure by Letters Patent is:

1. A button comprising a shell having an integral hollow hub, a hollow die within said 50 shell, said die having a shoulder in its upper portion resting on the upper edge of the hub of said shell, the said die having a central arcuate portion adapted to curl a fastener down within said die and a cap on said shell 55 and bearing against the arcuate portion only of said die.

2. A button comprising a shell having an integral hollow hub, a hollow die within said 60 shell, said die having a peripheral shoulder in its upper portion resting on the upper edge of the hub of said shell, the upper wall of the die having an annular portion extending towards the center, a dome shaped portion merging with said annular portion centrally 65 of the upper wall and adapted to curl the

prong of a fastener down within said die, a cap on said shell and said cap having raised portions stamped therein and the raised portion of the cap located over the dome shaped portion of the die.

3. A button comprising a shell having an integral hollow hub, the bottom wall of the hub being perforate, a hollow die within said shell, the bottom wall of the die being perforate and registering with the perforate portion of the hub, said die having a peripheral shoulder resting on the upper edge of the walls of the hub, the top surface of the die having an annular flat portion, a hollow dome merging with the inner wall of the 30 annular portion, the said dome shaped portion of the die adapted to curl the bottom of a fastener down within the die, a cap having stampings formed thereon, some of the stampings of the cap located over the dome shaped portion of the die and the said dome shaped portion supporting the cap centrally thereof.

4. A die for a tack button having a slightly tapered peripheral wall, a perforate bottom wall, a peripheral shoulder near the upper portion of the die, said die provided with a closed top wall, said wall being flat for a distance towards the center and said wall being dome shaped centrally thereof and adapted to curl the prong of a fastener within the die.

5. A hollow die for a button comprising a perforate bottom wall and slightly tapering side walls, a peripheral shoulder near the upper edge of the die, a top wall having an annular flat portion, a central dome merging with the annular portion and the dome shaped portion adapted to curl the prong of a tack fastener.

6. A hollow die for a button comprising a perforate bottom wall and slightly tapering side walls, a peripheral shoulder at the upper edge of the side walls and an annular top wall, a dome shaped portion merging with the annular top wall and the radius of the dome being less than the radius of the die.

In testimony whereof we affix our signatures.

LEONARD R. CARLEY.
